ATTORNEYS

UNITED STATES PATENT OFFICE.

JOHN W. SIMMONS, OF HAGERSTOWN, MARYLAND.

DESIGN FOR A BUTTON.

SPECIFICATION forming part of Design No. 32,142, dated January 23, 1900.

Application filed December 18, 1899. Serial No. 740,829. Term of patent 14 years.

To all whom it may concern:

Be it known that I, JOHN W. SIMMONS, a citizen of the United States, residing at Hagerstown, in the county of Washington and State of Maryland, have invented and produced a new and original Design for a Button, of which the following is a specification, reference being had to the accompanying drawings, forming part thereof.

10 In the accompanying drawings, Figure 1 is a plan view, and Fig. 2 an edge or side view, of a button or badge embodying my design.

The leading feature of the design consists in a representation of the insect com-

monly known as the "ant" and the human eye open.

A minor feature of the design is a panel or bordered space underneath the eye.

What I claim is—

The design for a button as herein shown and described.

In testimony whereof I have signed my name to this specification in the presence of two subscribing witnesses.

JOHN W. SIMMONS.
